UNITED STATES PATENT OFFICE.

FRIEDRICH PANSE, OF NEW YORK, N. Y.

PLAITING-MACHINE.

SPECIFICATION forming part of Letters Patent No. 331,432, dated December 1, 1885.

Application filed February 24, 1885. Serial No. 156,686. (No model.)

To all whom it may concern:

Be it known that I, FRIEDRICH PANSE, of the city of New York, in the county and State of New York, have invented a new and Improved Plaiting-Machine, of which the following specification is a full, clear, and exact description.

This invention relates to a machine for plaiting crimped or fluted fabric. The plaiting-machines heretofore in use were made for the manufacture of plaits out of plain fabric, and the fabric was generally stretched between two needles or plates while the plait was formed. With crimped fabric the stretching would be impracticable, inasmuch as the crimps would thereby be straightened out.

The invention therefore consists, principally, in the combination of two gage-plates so arranged that the fabric is made to form a loose fold between them, the fold being afterward pressed and treated in proper manner to form the plait.

The invention also comprises mechanism for throwing the fabric up between the gage-plates and for adjusting the size of the folds.

It also consists in the various features of improvement hereinafter more fully pointed out.

In the accompanying sheets of drawings, Figure 1 is a top view of the machine. Fig. 2 is a vertical section on the line $x-x$, Fig. 1. Fig. 3 is a detail view of the gage-plates and intervening presser-foot and spring; Fig. 4, a side view of the machine, (left side of Fig. 1; Fig. 5, a detail sectional view of the feed mechanism; Fig. 6, a front view of the machine above the work-plate, (the front gage-plate being removed;) Fig. 7, a partial bottom view of the work-plate; Fig. 8, a detail view of the front gage-plate. Fig. 9 shows the crimped fabric as it enters the machine, and Fig. 10 the completed plaiting as it leaves the machine.

The letter A represents the machine-frame, carrying a horizontal work-plate, a. b is the front gage-plate, and c the rear gage-plate. The gage-plates are constructed in such a manner that the front plate grasps the fabric and pushes a fixed portion thereof toward the rear plate. Between the plates when they are brought together a narrow space or chamber, d, always remains, and the fabric bulges up in

this space to form a fold. This fold is subsequently acted upon by a presser-foot, and is fed out in manner hereinafter described.

I shall first describe the mechanism for operating and adjusting the gage-plates and the supplemental devices for forming the fold.

A power-shaft, B, is hung across the machine, and may be revolved by hand or otherwise. A cam, e, on this shaft imparts, by toggle-levers f f', intermittent partial revolutions to a shaft, g, hung across the front of the machine. To the shaft g are keyed two arms, h, and to trunnions on these arms are in turn pivoted two rods, i, to which the front gage-plate, b, is rigidly secured. By operating the power-shaft as thus far described horizontal reciprocating motion is imparted to plate b. The rear gage-plate, c, is free to move vertically up and down between stationary guides. It receives its motion from a shaft, j, to which it is connected by means of arms k, that are keyed to the shaft and swiveled to the gage-plate. The shaft j receives intermittent partial revolutions by suitable cam-connection with the power-shaft B.

l l are two pins attached to and projecting forward from the face of gage-plate c. These pins engage beneath two lugs, m, formed on the gage-plate b, Fig. 1, and form ways on which the plate b slides to and fro.

As the front plate has a swivel-connection with its shaft g, it is evident that the plate is free to rise and fall, and thus as the rear plate, c, rises it will force up plate b by means of pins l, while when the plate c falls the plate b will likewise fall by gravity.

After a length of fabric is introduced into the machine a partial revolution of the power-shaft will bring the gage-plates into the position shown in Fig. 3—that is to say, the plate b is in its foremost position, and both it and plate c are in their lowermost position. A further motion of the work-shaft will now cause the plate b to move toward plate c. In this motion the plate b, turning on the trunnions, will assume a more and more vertical position, its lower edge sweeping across the work-plate. The plate b is finally brought into the position indicated by dotted lines in Fig. 3, in which it is at its closest proximity to plate c. In this position both

plates are substantially parallel, both are in their lowermost position, and between them the empty space or chamber *d* is formed. During the advance of plate *b* it has grasped the 5 fabric under its lower edge and crowded it along with it, so that all the fabric between the plates in their most distant position is collected in the space *d*. Thus the fabric forms an upwardly-projecting loose fold in said chamber *d*. After the plate *b* has advanced in manner described both plates are raised, (plate *c* by shaft *j*, and plate *b* by pins *l*,) and the plate *b* is moved back into its first position.

The motion of plate *b* is capable of double 15 adjustment. The first is designed to change the size of chamber *d*, or, in other words, to regulate the minimum distance between plates *b* 20 *c*. The second permits the outward throw of plate *b* to be altered, so that a greater or less 25 quantity of fabric is grasped. The first adjustment is obtained by varying the length of arm *f*. To this effect the arm *f* is made of two pieces, Figs. 1 and 4, connected by a bolt that passes through a slot in one of the pieces. 30 The second adjustment is obtained by a screw, *n*, passing through the front of the machine-frame. The end of the screw strikes against the lower end of the arm *f'*, and thus by turning the screw in or out the arm *f'* (and consequently plate *b*) is permitted to move forward to a lesser or greater extent.

D is the presser-foot, placed between plates *b c*. This foot reciprocates vertically between stationary guides and receives its upward motion from a cam, *o*, while springs *p* throw it down. When the gage-plates are brought together, the presser-foot descends and bears 35 upon the center of the fold just formed. Beneath the presser-foot is the reciprocating feed-rack hereinafter described, and as the gage-plates rise to release the fabric the presser-foot holds it against the feed. After the feed ceases to act the presser-foot is raised to the position shown by full lines in Fig. 3. The gage-plate *b* is slotted, Fig. 8, to permit the presser-foot 40 to project forward of said plate when the plates *b c* are in proximity. Between gage-plates *b c* the work-plate *a* is provided with two slots, Figs. 1, 3, and 6, and through 45 these slots project two (more or less) flat upwardly-curved springs, *q*. These springs serve to bulge the fabric between the plates as the plate *b* advances. On the return motion of plate *b* the springs *q* are made to descend beneath the work-plate, so as to be out of the 50 way. To this effect they are connected beneath work-plate *a* to a rod, *r*, Fig. 7, the ends of which project upwardly through apertures in said plate. These ends are directly 55 beneath the presser-foot plate *D*, and thus as the latter descends the ends of rod *r* are pushed down. The rod in turn will force the springs *q* down.

The feed acts beneath the presser-foot *D*, and 60 also beneath a second presser-foot, *E*, placed directly back of foot *D*. The foot *E* is free to rise and fall. It presses the middle of the

plait against the feed, and is heated by gas led into its interior, so as to fix the plait in its compressed condition.

The feed consists of a toothed rack, *F*, to which reciprocating and oscillating motion may be imparted. The means shown in the drawings, Fig. 5, consist of a cam, *s*, and block *t*, to the front of which the rack is attached. 70 The block *t* is pivoted to the machine-frame, the pivot passing through a longitudinal slot in block *t*. As the cam revolves, it bears against the rack and raises it. Then the edge of the cam bears against edge of block *t*, and 75 causes the rack to move in its raised position. As soon as the cam has turned far enough to release the edge of the block the latter is thrown forward by a spring, *u*, while the rack *F* falls down.

The relative operation between the presser-foot and the rack is as follows: After the fold has been formed between plates *b c* in manner described both presser-feet are down. The rack *F* is then raised to grasp the fabric, and 90 it begins its motion, carrying the fabric with it. After the backward motion of the rack ceases the presser-foot *D* is raised, and the rack then swings downward and comes forward. The foot *E*, resting upon the rack, is raised with 95 the same, and falls down as the rack descends.

The machine is to be provided with an attachment for pressing threads over the flattened part of the fabric. Two parallel threads are fed between rack *F* and presser-foot *E*, 100 and are secured to the fabric by pressure and heat or by other suitable means. This, however, has already been described in my Patent No. 214,788, and forms no part of the present invention. In place of springs *q*, I may employ lugs projecting upward from the work-plate.

I claim as my invention—

1. The combination of gage-plate *c*, receiving vertically-reciprocating motion from a power-shaft, *B*, with gage-plate *b*, which receives horizontal reciprocating motion from said power-shaft, the plates being substantially parallel when at their greatest proximity, substantially as specified.

2. The combination of gage-plate *c* with gage-plate *b*, which receives horizontal reciprocating motion from power-shaft *B*, and with work-table *a*, the plate *b* bearing upon said table when approaching plate *c* by connection with said power-shaft, substantially as specified.

3. The combination of gage-plate *c*, operated from shaft *B*, with gage-plate *b*, operated from said shaft, and with intervening spring, 125 to operate substantially as specified.

4. The combination of plate *c*, operated from shaft *B*, with slotted plate *b*, operated from said shaft, and with presser-foot *D*, the latter projecting through the slot in plate *b* when 130 said plate is in proximity with plate *c*, substantially as specified.

5. The combination of shaft *B* with levers *f f'*, the lever *f* being sectional, and with shaft

- g, imparting motion to plate b, substantially as specified.
6. The combination of shaft B with levers f f', shaft g, and plate b, connected to said shaft, and with screw n, bearing against lever f', substantially as specified.
7. The combination of plates b c, operated from shaft B, with presser-foot D, spring q, and rods r, substantially as specified.
- 10 8. The combination of vertically-reciprocating plate c, having pin l, with plate b, having lug m, the plate b receiving horizontal motion from shaft g, and vertical motion from pin l, substantially as specified.
- 15 9. The combination of reciprocating plate c and oscillating plate b, receiving motion from
- shaft B, with presser-foot D, cam o, spring p, presser-foot E, rack F, and cam s, substantially as specified.
10. The combination of plates b c, receiving 20 motion from shaft B, with spring q, presser-feet D E, rack F, and cams o s, for imparting motion to the parts D F, substantially as specified.
11. The combination of plates b c and shaft 25 B with presser-feet D E, rack F, slotted block t, spring u, and cams o s, substantially as specified.

FRIEDRICH PANSE.
